Primary Examiner—Ian Simmons*Assistant Examiner*—Wan Laymon(74) *Attorney, Agent, or Firm*—Foley & Lardner LLP(57) **CLAIM**

We claim the ornamental design for a projector mounting device, as shown and described.

DESCRIPTION

FIG. 1 is a perspective view of a projector mounting device showing our new design;

FIG. 2 is a top plan view thereof;

FIG. 3 is a first side view thereof;

FIG. 4 is a second side view thereof;

FIG. 5 is a third side view thereof;

FIG. 6 is a fourth side view thereof; and,

FIG. 7 is a bottom plan view thereof.
